F. W. LEE,
FOUNTAIN PEN.

APPLICATION FILED NOV. 12, 1918. RENEWED NOV. 11, 1919.

1,325,443.

Patented Dec. 16, 1919.

UNITED STATES PATENT OFFICE.

FRANK W. LEE, OF SPOKANE, WASHINGTON.

FOUNTAIN-PEN.

1,325,443.

Specification of Letters Patent. Patented Dec. 16, 1919.

Application filed November 12, 1918, Serial No. 262,108. Renewed November 11, 1919. Serial No. 337,173.

To all whom it may concern:

Be it known that I, FRANK W. LEE, a citizen of the United States, and a resident of Spokane, in the county of Spokane and 5 State of Washington, have invented new and useful Improvements in Fountain-Pens, of which the following is a description.

This invention relates to fountain pens and has for its primary object to provide a 10 means whereby the ink supply of the reservoir thereof may be easily replenished.

A further object of the invention is to provide a pen which is compact in structure, reliable in operation and inexpensive 15 to manufacture.

Other objects and advantages of the invention will be apparent during the course of the following description taken in connection with the accompanying drawings.

20 In the drawings, forming a part of this specification and wherein like numerals are employed to designate like parts throughout the same,

Figure 1 is a side elevation of the device 25 embodying my invention,

Fig. 2 is a top plan view of the same,

Fig. 3 is a central vertical longitudinal sectional view, the reservoir being shown as 30 filled with ink and the several elements in a position for writing,

Fig. 4 is a similar view to that of Fig. 3, the several elements thereof being in a position for facilitating the filling of the reservoir.

35 Fig. 5 is a transverse sectional view taken on line 5-5 of Fig. 3, and,

Fig. 6 is a transverse sectional view taken on line 6-6 of Fig. 3.

In the drawings, wherein for the purpose 40 of illustration is shown a preferred form of my invention, the numeral 10 indicates a barrel having one end thereof closed as shown at 11. Within the closed end 11 there

45 is arranged a tube 12 to one end of which is connected a rubber reservoir 13 adapted for the reception of a quantity of ink as shown at 1. The tube 12 at its outer end is provided with an ejecting port 14 and an injecting port 15. The injecting port as clearly

50 shown in Figs. 3 and 4 is retained in registration with an ink receiving depression 16 carried by a pen point 17 which is secured by means of ears 18 to a support 19, the ears 18 being adapted to extend an appreciable distance into the sides of the support

19 as clearly shown in Fig. 5. The injecting port 15 is adapted to be closed by a spring metal valve 20 which is slidably mounted upon the barrel 10 and retained in position thereupon by means of a yoke 21 60 partially encircling the barrel 10 and retained in engagement thereon as clearly shown in Fig. 6.

As a means for collapsing the reservoir 13 there is provided a plate 22 which is connected by means of links 23 to the barrel 10, the links being pivotally connected to the plate 22 and the barrel 10 by means of pivots 24 and 25 respectively. As a means for moving the plate 22 from the position shown 70 in Fig. 3 to the position shown in Fig. 4 there is provided a link 26, one end of which is connected to the plate 22 as shown at 27 while the other end thereof is connected, as shown at 28, to a reciprocating cap 29, the 75 cap being mounted upon the end of the barrel 10 as clearly shown in Figs. 3 and 4.

In use, when it is desired to refill the reservoir 13, the cap 29 is moved to the position shown in Fig. 4 whereupon the plate 22 is 80 moved to the position clearly shown in Fig. 4, thereby depressing or collapsing in reservoir 13. The pen is then dipped into a suitably quantity of ink whereupon the cap 29 is moved to the position shown in Fig. 3 85 allowing the plate 22 to move to the position shown in Fig. 3. The release of pressure upon the reservoir 13 permits the same to assume a normal position whereupon a quantity of ink, assuming that the valve 20 is 90 moved to the position shown in Fig. 4, is drawn into the reservoir 13. After a desired quantity of ink is drawn into the reservoir 13 the valve 20 is moved to the position shown in Fig. 3, thus rendering the device 95 capable of use in that capacity for which it is obviously intended.

It is to be understood that the form of my invention herewith shown and described is to be taken as a preferred example of the 100 same, and that various changes in the shape, size and arrangement of parts may be resorted to without departing from the spirit of the invention or the scope of the subjoined claim.

Having thus described my invention, what I claim as new and desire to secure and protect by Letters Patent of the United States is:

A fountain pen comprising a barrel hav- 110

ing a closed end, an elongated support carried at the closed end of said barrel, said support being provided at its sides with depressions, an elongated tube mounted within 5 the closed end of said barrel and provided with injecting and ejecting ports, said tube extending an appreciable distance into said barrel and an appreciable distance over the end of said support, a pen point confined between 10 said support and the outer end of said tube, said pen point being adapted to receive

upon the outer face thereof ink from the ejecting port of said tube and provided with ears adapted to extend into the depressions of said support, a yoke secured to the closed 15 end of said barrel, a valve for closing the injecting port, said valve being adapted to slide within said yoke, a collapsible reservoir carried within said barrel and connected to said tube, and means for collapsing said 20 reservoir.

FRANK W. LEE.
